SAILBOAT

John Coulter, 5909 Adderley Drive,
Long Beach, Calif. 90808

Filed Feb. 20, 1968, Ser. No. 10,640

Term of patent 14 years

U.S. Cl. D71—1
Int. Cl. D12—06

FIG. 3

FIG. 1

FIG. 2

I claim:

The ornamental design for a sailboat, as shown and described.
